UNITED STATES PATENT OFFICE.

NICHOLAS WITSCHI, OF JERSEY CITY, NEW JERSEY, ASSIGNOR TO THE AMERICAN LITHOGRAPHIC COMPANY, OF NEW YORK, N. Y.

DESIGN FOR A LABEL.

SPECIFICATION forming part of Design No. 29,865, dated December 27, 1898.

Application filed November 28, 1898. Serial No. 697,707. Term of patent 7 years.

To all whom it may concern:

Be it known that I, NICHOLAS WITSCHI, a citizen of the United States, residing at Jersey City, in the county of Hudson and State of New Jersey, have invented and produced 5 a new and original Design for a Label, of which the following is a specification, reference being had to the accompanying drawing, forming a part thereof.

10 My design is intended for use as a label.

In the accompanying drawing the design is shown on a rectangular panel.

15 The design comprises a rectangular panel having thereon a large peach, the stem still adhering to a small branch which extends diagonally across the panel upon which this drawing is shown. The branch is in full leaf. To the left of the design is shown a scroll-work border and in the lower right-hand corner a ribbon panel with convoluted ends. 20

I claim—

The design for a label as herein shown and described.

In testimony whereof I, NICHOLAS WITSCHI, affix my signature in presence of two witnesses. 25
